INVENTOR
Franklin R. White
BY
George Cook & Sons
ATTORNEYS

UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

Application filed March 8, 1924. Serial No. 697,938.

To all whom it may concern:

Be it known that I, FRANKLIN R. WHITE, a citizen of the United States, and a resident of Waterbury, in the county of New Haven and State of Connecticut, have made and invented certain new and useful Improvements in Buttons, of which the following is a specification.

My invention relates to buttons and particularly to that type or class of buttons which are formed of malleable metal and sized or shaped by the action of heading or swedging dies. This type of button is ordinarily made from a wire rod blank, and, due to the manner in which it is formed, the top of the button can be of any desired configuration or possess any desired ornamentation. Heretofore, however, in forming the button with irregularly shaped heads, it was not thought possible to provide the head of the button with an ornamental cap. There is a large class of trade, however, which requires buttons having a top of brass or similar appearing metal, and it is accordingly the object of my invention to provide a button and a method of forming the same whereby the body of the button is swedged or formed from a suitable malleable metal, such as aluminum or zinc, and to permanently affix and attach thereto an ornamental cap, the body of the button and the cap being subjected to the action of suitable dies prior to the completion of the button, whereby both the head of the button and the ornamental cap will be caused to take up the irregular and ornamental shape and be suitably inscribed or ornamented and at the same time a most rigid attachment obtained between the cap and the head of the button.

With the foregoing and other objects in view, my invention consists in the improved button and method of forming the same illustrated in the accompanying drawings and hereinafter described and claimed, and in such variations and modifications thereof as will be obvious to those skilled in the art to which my invention relates, it being understood that changes may be made within the scope of what is claimed without departing from the spirit thereof.

The preferred embodiment of my invention is disclosed in the accompanying drawings, wherein:

Figure 1 is a view in elevation of a rod or wire from which my button is formed;

Figure 2 is a view in vertical section of the body of the button and the separate cap as they come from the first stamping or forming operation;

Figure 3 is a view in side elevation and partially in section illustrating the cap as mounted upon the top of the button and the two subjected to the second set of operating dies whereby the rim of the cap has been turned inwardly and compressed against the side walls of the top of the button, the latter also being swedged inwardly by the pressure of the dies;

Figure 4 is a bottom plan view of the foregoing;

Figure 5 is a bottom plan view of the body of the button and cap after being subjected to the action of the third or finishing set of dies;

Figure 6 is a view in section taken on the line 6—6 of Figure 5;

Figure 7 is a view in vertical section of my improved button, the hub in this instance being provided with a hard metal anchor for the fastener;

Figure 8 is a view in vertical section illustrating my improved button as attached to garment material.

Referring specifically to the several views, wherein similar reference numerals designate corresponding parts throughout, the rod 10 represents a conventional form of wire such as used in heading machines for the formation of rivets and in the present instance is preferably made of aluminum, zinc or other suitable material which may be readily formed into buttons without requiring undue pressure or force to be exerted by the heading machine. The wire is automatically cut to length as illustrated by the dotted lines 11, and each length or slug after being subjected to the first heading or forming dies (not shown) will be composed of an upper flange 12 and a hub 13 into which projects the opening 14. This first-stage blank receives thereon a suitable cap

15, preferably formed of brass or some other suitable and ornamental material, and the cap and first-stage blank are then subjected to suitable dies (not shown) whereby the 5 downwardly extending rim 16 of the cap is inwardly bent, as illustrated in Figure 3, and the pressure whereby the inward bending of the rim of the cap is accomplished also correspondingly tapers the flange 12 of 10 the first operation blank.

The second operation blank, as illustrated in Figure 3, is then subjected to the action of suitable dies (not shown) and considerable pressure is exerted upon the flange 12 15 and the cap 15, causing the metal of the flange 12 and the metal of the cap to be forced outwardly and in a sense extruded, considerably enlarging the diameter of the flange 12 and at the same time reducing the 20 thickness of the same and thereby forming the head 17 of the button, as illustrated in Figure 6. As illustrated in Figure 5, the head of the button is preferably given an irregular shape, as at 18, which irregular 25 shape may partake of the nature of a four-leaf clover or any other desired shape. In this swedging and heading operation, the metal 12 of the flange of the first operation blank and the metal of the cap are compressed together under enormous pressure 30 and in a sense amalgamated and joined together so as to practically form a rigid unit, particularly so in that the rim 16 of the cap now extends completely around the head 35 of the button as at 19. Furthermore, attention is called to the fact that the under side 20 of the head is smooth and that the metal of the body of the button and the metal of the cap form a continuation one of the other, 40 so that the button not only presents a neat, pleasing and ornamental appearance, but the under surface is smooth and the button accordingly extremely practical and usable. The cap is preferably formed of brass and 45 thus makes the button ideal for use in the overall trade, wherein brass buttons are usually specified.

The button as illustrated in Figures 5 and 6 is then subjected to the action of one further set of dies whereby the opening 14, 50 which extends inwardly into the hub, is transformed into a chamber 21, as illustrated in Fig. 8, the extremity of the hub being contracted as at 22, thus providing a restricted opening leading into the chamber 21.

The button is ordinarily held to the garment by the use of the tack fastener 23 which is headed and turned within the restricted chamber in the customary manner.

In Figure 7 I have disclosed a somewhat modified form of my button wherein the hub 24 is provided with the customary form of anchor 25 which is formed of hard metal and is thus capable of receiving and head-

ing or turning over a tack fastener which is also formed of hard metal, such as steel.

Having thus described and explained my invention, I claim and desire to secure by Letters Patent:

1. A button composed of a body including a head and a hub, the latter being provided with a fastener-receiving chamber therein, and a cap mounted upon said head, the head and cap being of irregular and ornamental configuration and with the cap provided with a rim extending around the head of the button and forming a continuation of the under side of the head. 75

2. A button composed of a body portion including a head and a hub, a cap mounted upon said head, and the head and cap formed to present an irregularly shaped periphery of the head and cap, the under portion of the cap being formed so that the 80 undersurface of the head and the said under surface of the cap form a continuing smooth, unbroken surface. 85

3. A button composed of a body portion including a head and a hub, the latter being provided with a fastening receiving chamber therein, a cap mounted upon said head, and the head and cap being formed to present an irregularly shaped periphery, the under portion of the cap having a rim 90 merging with the under side of the head to form a smooth and unbroken surface. 95

4. A button composed of a body portion including an annular head and a cap fitting over said head, said cap and said head being formed to present an irregularly shaped periphery of the cap and head, the cap provided with a rim extending around the under surface of the head and forming a continuation and unbroken surface with the 100 under surface of the head. 105

5. A button composed of a body including a head and a hub, a cap mounted upon the head and said cap forming a non-separable unit, the periphery of the head and cap being irregular in shape, and the face of the cap provided with an ornamental configuration thereon, said cap provided with a rim merging with the under surface of the head to thereby present a smooth and 110 unbroken surface. 115

6. A button formed of metal having a hub and circular head, a circular cap mounted on said head and the head and cap formed to present an irregularly shaped head and cap with respect to their periphery, the cap merging with the under surface of the button head to form an unbroken surface. 120

7. A button formed from a soft metal blank, the head of which is circular in outline, and the hub of which is provided with a receiving chamber therein, a cap of hard metal corresponding with the shape of the head of the blank, and the cap and head formed to present an irregularly shaped 125 130

periphery, symmetrical in outline, an ornamentation formed on the cap, and the cap provided with a rim that lies flush with the under surface of the head to present a substantial integral head and cap.

8. A button formed from a soft metal blank the head of the blank being circular in outline, a hub formed on said head, a cap of hard metal corresponding to the shape of the blank and the cap and the head being shaped to thus tightly secure the cap to the head and to also form the cap and

head ornamentally in configuration, the configuration extending into the periphery of the head and cap, thus presenting an irregular and symmetrical periphery for the button head.

Signed at Waterbury, in the county of New Haven and State of Connecticut, this sixth day of March A. D. 1924.

FRANKLIN R. WHITE.
